UNITED STATES PATENT OFFICE.

ANNA C. CLARKE, OF SCRANTON, PENNSYLVANIA.

SEWAGE SYSTEM FOR RAILWAY-CARS AND THE LIKE.

1,200,080.

Specification of Letters Patent.

Patented Oct. 3, 1916.

Application filed October 5, 1912. Serial No. 724,059.

To all whom it may concern:

Be it known that I, ANNA C. CLARKE, a citizen of the United States, residing at Scranton, county of Lackawanna, State of Pennsylvania, have invented certain new and useful Improvements in Sewage Systems for Railway-Cars and the like; and I do hereby declare the following to be a full, clear, and exact description of the invention, such as will enable others skilled in the art to which it appertains to make and use the same.

This invention relates to sewage systems for railway cars and other vehicles of the general character disclosed in my former Patent No. 957,933, dated May 17, 1910, and has for its object to provide such system with means for diverting the sewage either into a receiving tank carried by the car, or to a free discharge outside of the car at will; to provide means for supplying flushing water under pressure to the apparatus, together with means for regulating the water pressure; and to provide an improved form of tank for receiving the sewage, associated with means for readily attaching and detaching the tank with respect to the car and establishing an efficient connection between the openings of the tank and the sewage waste pipe and the vent pipe when the tank is adjusted to position in its supporting devices.

The invention is illustrated in the accompanying drawings, in which—
Figure 1 is a side elevation partly in section of the body of a railway car having the invention applied thereto. Fig. 2 is an end view of the car body, partly broken away to illustrate the relative arrangement of the parts of the sewage system. Fig. 3 is a longitudinal vertical section through the improved sewage receiving tank. Fig. 4 is an end view showing a tank closure and its attaching means. Fig. 5 is an end view of the tank with the closure removed. Fig. 6 is a section of one end of the tank showing the means for securing the closure thereto. Fig. 7 is a sectional view of the three-way valve for directing the sewage into the tank or to the open discharge. Fig. 8 is a detail view of one of the tank supporting beams. Figs. 9 and 10 are front and side elevations of the tank supporting brackets by which the beams are carried.
Referring to the drawings, A indicates the body of a standard passenger car pro-

vided with the usual toilet accessories, of which 1 indicates the closet bowl to the discharge end of which is attached a fitting provided with a three-way valve 2, one side 60 of which connects with a sewage pipe 5 running toward the middle of the car and adapted to be attached at its free end to the inlet of a sewage receiving tank, to be hereinafter described. The other side of 65 the three-way valve is connected with a pipe 3, provided with an open discharge to direct the sewage out of the car and on to or adjacent the right of way. The said three-way valve 2 is provided with a suitable 70 handle 4, which is preferably extended to a point outside of the toilet compartment, so as to be accessible to the proper person on the car or train to operate the valve to direct the sewage either into the receiving 75 tank or to the open discharge on to the right of way.

It will be understood that the invention is not limited in its application to sewage from a closet bowl, but may also be applied 80 to the disposal of waste from basins, sinks, lavatories and other accessories of like nature common to railway cars of the usual type.

A suitable storage tank 6 for flushing 85 water is mounted at any convenient location in the vicinity of the toilet compartment and is adapted to be connected with an external water supply by means of a suitably valved pipe 7. The upper part of the tank 90 is provided with an outlet pipe 10, which extends downward into the body of the tank to a point near the bottom thereof and is connected at its other end with the usual inlet valve of a flush tank 11, which latter 95 is connected by flush pipe 12 with the bowl 1. In order to supply the necessary pressure to force the water from tank 6 into the flush tank 11 and to maintain an equal pressure of water at all times, the tank 6 is 100 preferably connected by a valved pipe 8 with the air pressure system of the train brakes, proper regulation of the air entering the tank being effected by a pressure regulator 9 located in pipe 8 adjacent the 105 bottom of the tank 6.

The sewage receiving tank 20 consists of a cylindrical shell, having secured at its ends, by rivets or other appropriate means, flanged rings 21, each formed on its outer 110 face with a seating rim adapted to co-operate with a corresponding seating rim on

the closure 24. Each of said end closures 24 is reinforced by crossed ribs formed integrally therewith, the upper ends of which are provided with hooks 26 adapted to engage and embrace lugs 22 on the rear face of the coöperating ring 21 as particularly illustrated in Figs. 4, 5 and 6. The opposite edge of each closure 24 and each ring 21 is provided with registering openings to receive a threaded bolt 28, the hole 23 in the ring being screw-threaded, while the hole 27 in the closure is slightly larger than the bolt 28 to admit of the latter being screwed into position and thereby draw the seating rim on the closure into close contact with the coöperating rim of the ring 21 and effectively sealing the tank against leakage. This construction of tank admits of the closures being readily removed for emptying the sewage and for flushing out the tank in the most effective manner.

The under side of the tank 20 is provided at each end with a saddle 37 riveted to the tank, said saddle having a relatively long flat horizontal bearing formed by pendent flanges 41 having pin-receiving lugs 38 extending therefrom. Each of said saddles is adapted to slidably engage an inverted channel bar 43, the opposite flanges of which are suitably notched as at 44 to receive locking pins 39 by means of which the tank is locked securely in position to the two beams 43. Said beams 43 are detachably supported in the forked ends 41 of brackets 40, which are disposed in pairs on opposite sides of the car and the ends of each beam 43 are locked to the brackets by pins 42 passing through perforations in the forked ends of the brackets 40 and engaging notches 44' in the pendent flanges of the beam. Said beam is strengthened by means of a truss rod 45 which is secured to the beam 43 by means of end blocks 47 and a central casting 46. The blocks 47 are provided with longitudinal perforations adapted to receive the end of a bar to admit of the beam being raised and lowered to position by the man whose duty it is to remove the full tanks and replace them with empty tanks.

50 The connection between the tank and the sewage pipe leading from the closet bowl or other toilet accessory is effected by means of the construction shown in Fig. 3. The discharge end of the sewage pipe or conduit 5 is tapered as at 5' to make a close air-tight fit with a rubber gasket or washer 31 which is securely held between a seating ring 30 riveted to the tank and coupling flange 32 secured to said ring by means of bolts or the like. The coupling flange 32 is provided with an opening somewhat larger in diameter than the end of the pipe 5' and said opening is screw-threaded on its interior to receive a screw-threaded plug to seal the tank when the same is removed from the

car and while it is being taken to the proper place to be emptied. The vent pipe 33 which is permanently attached to the car and passes upward through the walls thereof to a point above the roof, is attached to the tank by a similar hermetic seal consisting of a rubber gasket 35 coöperating with the tapered end 33' of said pipe 33, said gasket being held between a seating ring 34 riveted to the tank and an interiorly threaded cap 36 adapted to receive a plug to seal the vent opening in the tank when the latter is removed.

In applying the invention to its intended use, the tank is secured to the car by two workmen, each of whom inserts a bar in the opening in block 47 and lifts the corresponding beam 43 until the locking pin 42 can be withdrawn, after which each of the beams 43 is lowered until its end rests upon the ground adjacent the railway track. The empty tank is then applied to the beams so that the saddles 37 engage the two beams and the said tank is shoved forward along the beams until the openings in the lugs 39 of the respective saddles come opposite the notches 44 in the beams 43 at which time the locking pins 39 are passed through the ears 48 and the notches 44, 44', whereby the tank is securely locked to the beams. The workmen then lift the ends of the respective beams by means of the bars engaging the blocks 47, until the free end of each beam engages the forked end 41 of the coöperating bracket 40, whereupon the locking pins 42 are passed through the perforations in the forked ends of the brackets and notches 44' in the beams, and the tank and its supporting beams thereby securely locked in position. It will be apparent that the tank may be applied to or removed from position from either side of the car, inasmuch as the supporting beams 43 are attached to brackets 40 in the same manner at each end. As the tank is thus moved to position, the sewage inlet opening and the vent opening to the tank are both brought into registry with the fixed tapered ends of the sewage conduit 5 and the vent pipe 33, with the result that said tapered ends are forced into close air-tight engagement with the rubber gaskets 31 and 35 respectively, mounted adjacent said openings. When the tank is to be removed from a car, the operation is reversed, that is to say, the beams 43 are cast loose from their bracket supports on one side of the car and the free ends of the beams dropped to the right of way. This separates the tank from the pipes 5 and 33, after which the fastenings between the tank saddles and the beams 43 are removed and the tank slid along the inclined beams 43 until free of the same, when it can be lifted by the workmen and conveyed to the place of ultimate disposal

of the sewage. After a full tank has been removed, an empty tank is applied to the beams and the latter adjusted to locked position, as hereinbefore described. As soon as the full tank has been removed, the sewage inlet opening and the vent opening are closed by means of screw plugs inserted by the workmen in caps 32 and 36 respectively, if found necessary. The full tanks may be conveniently handled by suitable trucks equipped with cranes for lifting the tanks thereon, and, of course, may be transported to any suitable or appropriate place for ultimate disposal of the sewage. The tanks are emptied by removing one of the closures 24, after which the other closure 24 may also be removed and flushing water turned into the tank, open at both ends, to effectively clean the tank.

20 The tank is intended to be used in all localities where contamination of the soil or of streams would be likely to occur from sewage discharged from the car, and when traversing such localities, the three-way valve 2 is turned to discharge all of the sewage from the car into the tank. When, however, the car is passing through sections where contamination of streams cannot occur or where contamination of the soil of the road bed is immaterial, the three-way valve may be adjusted by the attendant on the car to direct the sewage by way of pipe 3 to the open discharge.

25 The entire system as hereinbefore described, is adapted to be applied to any standard railway car or similar conveyance, without materially changing the usual form or arrangement of standard sewage appliances, it being necessary only to attach the tank supporting devices to the under framing of the car, to mount the water storage tank and its air pressure connection at some point convenient to the toilet compartment, and to apply the three-way valve and its 30 connected conduit pipes to the discharge outlet of the bowl or other toilet appliance.

What I claim is:—

1. In a sewage system for cars and the like, a sewage receiving tank, and means for removably securing the tank to the car comprising pendent brackets on the car frame, beams detachably supported by said brackets, saddle pieces on the tank slidably mounted on said beams, and means for locking the saddle pieces to the beams.
2. A sewage system for cars and the like, comprising a receiving tank having a removable end and means for detachably sup-

porting the tank from the car including opposite pairs of pendent brackets having 60 forked ends, beams extending between the brackets of each pair and occupying the forked ends thereof, pins for locking the beams to the brackets, saddle pieces attached to the tank engaging the beams, and means 65 for locking the saddle pieces to the beams.

3. A sewage system for cars and the like, comprising a receiving tank having inlet and vent openings, soil and vent pipes secured to the car having rigid extremities 70 adapted to enter and be withdrawn from said openings when the tank is raised and lowered to and from its operative position, and means for detachably supporting said tank on the car comprising pendent brackets on the car, and tank supporting beams detachably supported by said brackets whereby the tank may be raised and lowered to and from its operative position and the inlet and vent openings made to engage with 80 and be withdrawn from said inlet and vent pipes respectively during the raising and lowering movements of the tank.

4. In a sewage system for railway cars, a receiving tank having an opening therein, 85 a pipe carried by the car having a rigid extremity, and means for detachably supporting and locking said tank on the car comprising a tank-supporting beam adapted to engage the under side of the tank and detachably associated with the car whereby the tank may be raised and lowered to and from 90 its operative position and the opening made to engage with or be withdrawn from said pipe extremity during the raising and lowering movements of the tank.

5. In a sewage system for railway cars, a receiving tank having an inlet opening, an inlet pipe carried by the car having a rigid extremity, and means for detachably supporting and locking said tank on the car comprising pendent brackets on the car, tank supporting beams detachably supported by the brackets whereby said tank may be raised and lowered to and from its operative position and the extremity of said inlet pipe made to engage in or be withdrawn from said inlet opening during the raising and lowering movements of the tank.

In testimony whereof I affix my signature, 110 in presence of two witnesses.

ANNA C. CLARKE.
